UNITED STATES PATENT OFFICE

165,757

ELECTRIC SADIRON

Murray Ireland, Elgin, Ill., assignor to McGraw
Electric Company, Elgin, Ill., a corporation of
Delaware

Application November 30, 1949, Serial No. 6,342

Term of patent 14 years

(Cl. D49—6)

To all whom it may concern:

Be it known, that I, Murray Ireland, a citizen of the United States, residing in Elgin, county of Kane, State of Illinois, have invented a new, original, and ornamental Design for an Electric Sadiron, of which the following is a specification, reference being had to the accompanying drawings, forming a part thereof, in which

Fig. 1 is a front perspective view of an electric sadiron, showing my new design;

Fig. 2 is a rear perspective view thereof;

Fig. 3 is a top plan view thereof;

Fig. 4 is a side; and

Fig. 5 is a front elevational view thereof.

The dominant features of the design reside in the portion of the device that is shown in full lines.

I claim:

The ornamental design for an electric sadiron, substantially as shown and described.

MURRAY IRELAND.
